(57) CLAIM

The ornamental design for a panty with integrated sanitary napkin, as shown and described.

DESCRIPTION

FIG. 1 is a front elevation view of a panty with integrated sanitary napkin showing our new design;
FIG. 2 is a rear elevation view thereof;
FIG. 3 is a right side elevation view thereof, the opposite side being a mirror image of the shown;
FIG. 4 is a top plan view thereof;
FIG. 5 is a bottom plan view thereof; and,
FIG. 6 is an isometric view thereof.
In the drawings, the broken lines represent stitching.
